UNITED STATES PATENT OFFICE.

ARANT J. KRAMER, OF PITTSBURGH, PENNSYLVANIA.

LOCKING DEVICE FOR MILK-BOTTLES AND OTHER OBJECTS.

1,188,459.

Specification of Letters Patent. Patented June 27, 1916.

Application filed December 11, 1914. Serial No. 876,650.

To all whom it may concern:

Be it known that I, ARANT J. KRAMER, a citizen of the United States, residing at Pittsburgh, in the county of Allegheny and State of Pennsylvania, have invented new and useful Improvements in Locking Devices for Milk-Bottles and other Objects, of which the following is a specification.

My invention relates particularly to devices for locking milk bottles against unauthorized removal when left at a customer's residence or other place.

The object of my invention is to provide a convenient and effective device in which a milk bottle may be placed, and locked against unauthorized removal; to provide a simple device, designated a keeper, for retaining the bottle in a holder so that it cannot be removed except when released by the opening of a door or from the interior of the residence or from the rear side of the wall or other support for the holder; and to provide a simple means for causing the retaining device, or keeper, to be removed out of locking position as soon as it has been released.

Other objects will appear hereinafter.

Referring to the accompanying drawings, Figure 1 is an elevation showing a form of my invention; Fig. 2, a cross-section of Fig. 1, parts being shown in plan; Fig. 3, an elevation showing the keeper unlocked, the door open, and the receptacle in dotted lines at a higher position than in Fig. 1; and Fig. 4, a plan of the receptacle and its holder. Fig. 5 is a section showing how the receptacle is secured to its support.

On the drawing the vertical support 1^a is a door casing or the like to which the door 27 is hinged. The block or strip 2^a to which the receptacle-holding plate 13^a is secured to the casing 1^a close to the door 27. The receptacle 6^a is secured to the strip 2^a by the hooks 10^a which extend upwardly from the metal strip 28 secured to the strip 2^a. The strip 28 is provided with three hooks 10^a in vertical alinement. When a full-sized bottle 7^a is to be deposited in the receptacle, the latter is hung on the lower two of the hooks, but when a shorter bottle is to be deposited in the receptacle, the latter is hung on the upper two hooks 10^a, the receptacle then taking the position shown in dotted lines on Fig. 3.

The keeper 11^a is arranged to be swung down on its pivot or hinge-pin 12^a so as to

lie over the top of the bottle 7^a when the latter is sealed in the receptacle 6^a, as shown on Fig. 1. The keeper carries the horizontal detent or catch 16^a which is yieldingly pressed toward the door 27 by the spring 18^a, and, when free to do so, extends toward the door a short distance beyond the keeper.

The operation is as follows: The door 27 being closed as shown on Fig. 2, and the keeper being swung to its upper position and held there by the spring 22^a, the bottle 7^a is placed in the receptacle 6^a. The keeper is then pulled down over the top of the bottle to the position shown in Figs. 1 and 2, whereupon the catch 16^a, which has been pushed partially into the keeper and has been constantly pushed by the spring 18^a against the plate 30 on the door 27, is forced by the spring 18^a into the hole 31 in the plate 30. When the door 27 is opened the plate 30 is moved away from the catch 16^a, whereupon the spring 22^a raises the keeper 11^a to its open position shown in Fig. 3.

When the keeper is locked in its lower position, as shown on Fig. 1, the top of the keeper is so situated with respect to the top of the bottle, that the bottle, when seated in the receptacle and on the support 8^a, cannot be lifted sufficiently to permit its bottom to be slid sidewise over the top of the receptacle. The flange of the keeper surrounds the upper end of the bottle and fits it sufficiently well to prevent the top of the bottle from being moved from beneath the keeper.

I claim—

1. In a device of the class described, a wall, a receptacle at one side thereof having means to prevent the bottle therein from moving laterally and downwardly, a keeper pivotally connected to the wall and having a portion arranged to be swung downwardly into the upward path of a bottle in the receptacle so as to prevent the bottle from being moved upwardly out of the receptacle and laterally from beneath the keeper, a door, a catch carried by the keeper and engageable by the door when closed to prevent the upward movement of the keeper until the door is opened.

2. In a device of the class described, a wall, a bottle receptacle secured thereto, and having means for preventing a bottle therein from moving laterally and downwardly, a pivoted keeper arranged to be moved into the path which the bottle takes while being

5 moved upwardly from the receptacle, a door adjacent to the keeper, and means associated with the keeper and the door whereby the keeper may be locked down when the door is closed and released when the door is opened.

3. In a device of the class described, a wall, a bottle holding receptacle, means whereby the latter may be secured to the 10 former at different heights, a keeper arranged to be moved over the upper end of a bottle when in the receptacle, so as to prevent its movement upwardly out of the receptacle, and means for releasably locking 15 the keeper when so moved.

4. In a device of the class described, a

Copies of this patent may be obtained for five cents each, by addressing the "Commissioner of Patents, Washington, D. C."

wall, a receptacle secured thereto and having means for preventing a bottle therein from moving laterally and downwardly, a keeper having a portion adapted to be moved 20 into the upward path of a bottle in the receptacle, a door, a catch engageable by the door for locking the keeper down when the door is closed to prevent the upward movement of the keeper until the door is opened. 25

Signed at Pittsburgh, Pa., this 9th day of December, A. D. 1914.

ARANT J. KRABER.
